Inventor,

James H. Wilson,

By Glenn S. Noble, Atty.

UNITED STATES PATENT OFFICE.

JAMES H. WILSON, OF CHICAGO, ILLINOIS.

PAIL.

1,385,413.

Specification of Letters Patent. Patented July 26, 1921.

Application filed January 27, 1919. Serial No. 273,323.

To all whom it may concern:

Be it known that I, JAMES H. WILSON, a citizen of the United States, residing at Chicago, in the county of Cook and State of Illinois, have invented certain new and useful Improvements in Pails, of which the following is a specification.

This invention relates to pails or containers which are especially adapted for paint or the like, and is particularly directed to the closure therefor and means of applying the same.

The objects of this invention are, to provide a pail or can so constructed that a fluid-tight top or closure may be readily applied thereto; to provide a pail having a novel cover and means for holding the same; to provide an improved method of applying a cover to a pail; and, in general, to provide such improvements as will be described more fully hereinafter.

In the accompanying drawings illustrating this invention:

Figure 1 is a side view of the pail with the upper part shown in section to illustrate the construction of the closure;

Fig. 2 is a detail showing a crimped rim; and

Fig. 3 is a detail showing the cover in closed position, and showing a slightly modified form of top.

It has been found more or less difficult to construct or manufacture pails of comparatively large size for paint or the like, with tops which can be readily applied and fastened by the paint maker after the pails have been filled, so as to make a substantially fluid-tight package for shipping.

In accordance with the present invention, I provide a pail which may be made in various sizes, but which in actual construction is usually made about twelve inches in diameter and fourteen inches in height, and is provided with a cover or closure adapted to form a substantially air-tight package.

As shown in the drawings, this pail comprises a body portion 4, which may be provided with one or more annular projections or beads 5, and with a cover protecting bead 6 adjacent to the upper end, which bead preferably projects beyond the others. The metal or the body is bent inwardly just above the bead 6 and then bent outwardly to form an annular inwardly projecting shoulder or flange 7 just below the rim 8. This flange or inwardly extending projection may, of course, be rolled or formed in

any suitable manner. The shoulder 7 forms a support for the cover 9, which consists of a thin metal plate adapted to fit within the rim 8. A gasket or packing ring 10 is provided to be inserted between the cover 9 and the shoulder 7.

The cover 9 is held in position by bending the rim 8 inwardly and down against the same, so as to press the cover tightly against the gasket. In order to do this, the rim is preferably corrugated, as indicated in Fig. 2, preparatory to bending it down over the cover. The pails are finished and supplied to the users in this condition. When the pail is filled, the rim 8 is readily bent or pressed inwardly and downwardly so as to press the cover 9 down against the gasket 10, which is compressed as indicated in Fig. 3. This is readily done by any suitable means, but preferably by a special closing machine which is provided for closing these pails. The edge of the cover may be depressed as shown at 11, Fig. 3, to receive the crimped rim.

It will be observed that changes may be made in the size and shape without departing from the spirit of this invention, and therefore I do not wish to be limited to the exact construction herein shown and described, except as specified in the following claims:

1. A pail comprising a body portion having an inwardly extending shoulder adjacent to the end, a cover formed of a single piece and fitting closely within the end, the portion of the body extending above said cover being crimped, whereby it may be bent inwardly to hold the cover in position.

2. In a pail, the combination of a body portion having an integrally formed shoulder adjacent to one end thereof, the portion of the body extending beyond the shoulder being crimped, a gasket adapted to engage with said shoulder, and a cover on said gasket of substantially the same diameter as the top of the pail.

3. In a container, the combination of a body portion having an integrally formed protecting bead adjacent to one end, and having the metal folded inwardly to form a shoulder adjacent to the end, a cover fitting in the end, the rim portion of the body around the cover being adapted to be bent inwardly against the upper surface of the cover to hold the cover in position.

JAMES H. WILSON.
